UNITED STATES PATENT OFFICE.

FRANK J. LAHER, OF PORTLAND, OREGON.

SHOCK ABSORBER.

Application filed May 21, 1925. Serial No. 31,820.

This invention relates to shock absorbing devices, particularly to the type commonly known as snubbers, employed for modifying excessive vertical oscillation of the load supporting springs of a vehicle, particularly such as are caused by irregularities in the road surface. Said devices are arranged to check the rebound produced by the return flexure of said springs rather than to modify the flexure itself.

Heretofore, the devices of the strap-and-drum type, of which this is a modification, have been characteristic by the provision of means which utilize friction, for the major part, in checking rebound. Friction produces severe wear and also often times produces squeaks and chatter unless lubricated and if lubricated the degree of lubrication affects the gripping force of the friction surfaces.

The object of my invention is to provide a device of this character with checking devices which comprise a revoluble drum element, the rotation of which, in the major part, is controlled by a spring element which is flexed or compressed oppositely to the load carrying spring, said two spring elements being connected by a flexible member.

A further object of my invention is to provide means for varying the degree of resistance of recoil of the vehicle springs inversely as the recoil movement progresses, the resistance force, however, remaining practically uniform. By arranging the devices in this manner a relatively large flexure or compression of the vehicle springs will be snubbed more severely than will a lesser distortion and thus the checking will be proportioned to the distortion, that is, the resistance of the coil spring will be increased in proportion to the probable recoil thereof.

I attain this object by providing a revoluble spring-controlled drum preferably provided with cable grooves arranged spirally relatively to the axis of rotation of said drum, the courses of said spirally wound cable thereon being arranged a progressively decreasing distance from the axis of rotation of said drum. Hence, the cable thus wound and connecting the body of the vehicle to the axle will exert a varying effective force against the load-carrying springs of the vehicle, said force increasing with the degree of flexure or compression of said springs.

A further object of my invention is to provide a device of this character with bear-

ing members for the drum which are adapted to interpose a substantial resistance to the rotation thereof, said bearing members being adjustable to vary said resistance. The interposition of a minor amount of resistance to rotation tends to prevent the drum from being spun about its axis at a greater rate than the cable or other flexible connection is unwound therefrom. Spinning of said drum might cause the cable or other flexible connection to be thrown from the guiding means provided therefor on said drum.

The details of construction and mode of operation of my device are hereinafter described with reference to the accompanying drawings, in which:

Fig. 1 is an elevation of my device with a portion of the housing being shown as broken away to disclose the spiral winding of said cable about the drum, the drum being shown as rotated as when the load-carrying spring is flattened to the maximum degree;

Fig. 2 is a section taken on the line 2—2 of Fig. 1, and shows the spiral arrangement of the cable way and the similar winding about the drum;

Fig. 3 is a transverse section taken on the line 3—3 of Fig. 1, showing the drum as rotatably mounted and the adjustable devices by which the resistance of the rotation of said drum may be adjusted; and

Fig. 4 is a section taken on the line 4—4 of Fig. 3, disclosing the arrangement of the retraction spring which acts against the return flexure of the load-carrying springs.

My device is preferably adapted to be carried upon one of the frame sides *a* of a vehicle and comprises a base *b*, a drum *c* rotatably carried by a trunnion *b'* which is preferably integral with said base, and a housing *d* which is adapted to enclose both said base and said drum; said cover being fastened to said base by screws or studs *e*, shown in Fig. 3. Said base is preferably fastened to said frame by bolts *f*; said bolts preferably being counter-sunk, as shown in Fig. 3, so that the tops of their heads lie flush with the inner surface of said base.

The drum is preferably provided with a spiral guideway *c'* which decreases progressively in diameter, relatively to the axis of rotation of said drum, from a point adjacent the base towards the face which extends away therefrom, as viewed in Fig. 2. Over said guideway the connecting cable

g is mounted, said cable being fastened to the drum by a clamp *h* and being fastened at its opposite end to the transverse axle *i* of the vehicle. Said frame side *a* is spaced 5 from the axle *i* by any type of supporting spring (not shown herein, or forming any part of this invention), said spring being compressed by the weight of the vehicle when the wheels, carried by the axle *i*, fall 10 into a rut, or the like.

I provide a spirally wound spring *j* within the hollow drum *c*, one end *j'* of which is fastened to said drum by bolts or screws *k* and the other end of which is fastened to 15 the base *b*, by a pin *l*. Said cable *g* is fastened to said axle in such a manner that the spring *j* is maintained at a flexed or compressed position and thus the cable is maintained taut between the point at which it 20 leaves the drum, and the axle. As the spacing between the axle *i* and the frame side *a* increases the distance between the drum and the axle correspondingly increases so as to cause the drum to be rotated against the action 25 of the coil spring *j* and to cause said cable to leave said drum at different points upon its cable way due to the rotation of said drum. The increase in spacing between said axle and said frame side and the resultant 30 rotation of the drum causes the point at which the cable leaves the drum to be progressively increased, due to the spiral arrangement of the cable way and thus the mechanical advantage of the pull of the cable over the action of the coiled spring is 35 progressively and proportionately increased by the spacing of said axle from said frame side.

Correspondingly, when the load-carrying 40 spring is flattened, as when one wheel falls into a rut, the spiral spring *j* will coil the cable upon its grooves. In as much as the groove decreases progressively in this direction the increase in coiling will produce 45 a relative advantage of said coil spring over said load-carrying spring so that the rebound of the latter will be more effectively restricted by the former.

To restrict the rotation of the drum *c* 50 upon the trunnion *b'*, I provide a bearing portion *m* for said drum which is made of material having a high co-efficient of friction, this material preferably being leather or other material commonly provided for 55 braking surface. Such material preferably is slightly flexible and compressible and I provide tapered adjusting members *n* which are arranged between said bearing member

and the hub *c'* of said drum so that the resistance to the rotation of said drum can 60 be adjusted. I provide a plate *o* upon the outer face of said drum which overlies said tapered members and provide a screw *p* which is threaded into said trunnion *b'*. The setting down of said screw tends to 65 move said plate *o* inwardly therewith and to force the tapered member *n* further into said hub and to force the bearing member more tightly against the trunnion to increase the resistance to the turning of said 70 drum. The head of said screw preferably extends through the housing *d* so that it can be adjusted without removing said housing.

I claim:

1. In a shock absorber of the character described, a base, a rotatable drum mounted thereon, a spiral spring controlling the rotation thereof, a flexible connection member wound about the periphery of said drum in a direction opposite to that in which said spring tends to rotate said drum, the mounting for said drum on said base having a face of relatively flexible material having relatively large co-efficient of friction, and means adjustable to vary the resistance of 85 said face to the rotation of said drum.

2. In a shock absorber of the character described, a base, a rotatable drum mounted thereon, a spiral spring controlling the rotation thereof, a flexible connection member wound about the periphery of said drum in a direction opposite to that in which said spring tends to rotate said drum, the mounting for said drum on said base having a face of relatively flexible material having relatively large co-efficient of friction, and a slit wedge-shaped member adjustable to vary the resistance of said face to the rotation of 95 said drum.

3. In a shock absorber of the character described, a base, a rotatable drum mounted thereon, a spiral spring controlling the rotation thereof, a flexible connection member wound about the periphery of said drum in a direction opposite to that in which said 100 spring tends to rotate said drum, the mounting for said drum on said base having a face of relatively flexible material having relatively large co-efficient of friction, means adjustable to vary the resistance of said face 105 to the rotation of said drum, and a housing carried by said base and enclosing the latter in said drum, said adjustable means extending through said housing.

FRANK J. LAHER.
